UNITED STATES PATENT OFFICE.

WALTER H. SMITH, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS.

1,352,483.

Specification of Letters Patent. Patented Sept. 14, 1920.

Application filed July 19, 1917. Serial No. 181,523.

To all whom it may concern:

Be it known that I, WALTER H. SMITH, a citizen of the United States, and a resident of Wilkinsburg, in the county of Allegheny and State of Pennsylvania, have invented a new and useful Improvement in Control Apparatus, of which the following is a specification.

My invention relates to control apparatus and especially to pneumatic control systems for governing electric railway motors and the like.

The object of my invention, viewed in its broadest aspect, is to provide a control system for electric motors which shall be almost entirely fluid-pressure-operated and governed, whereby practically all electric circuits are eliminated, thus producing a system that is less expensive to manufacture and maintain in operation than the present all-electric or electro-pneumatic control systems.

More specifically stated, it is one object of my invention to provide an all-pneumatic multiple-unit control system which shall be capable of effecting automatic control of one or more dynamo-electric machines in a manner analogous to that now provided by all-electric or electro-pneumatic control systems and which embodies regulating and safety features corresponding to those of the prior art, such as are employed in the familiar types of electric railway vehicles.

Viewed from another angle, it is an object of my invention to provide a fluid-pressure-operated control system, primarily governed by manually actuated pneumatic means, together with pneumatic regulating devices that are actuated in accordance with the current traversing the governed machines, whereby the automatic operation of the system closely corresponds to present electrically-governed automatic control systems.

Other minor objects of my invention, relating to the structure and correlation of various parts of the apparatus embodied in my system will become evident from the following detailed description and are pointed out with particularity in the appended claims.

In the accompanying drawings, representing my invention, Figure 1 is a view, partially in section and partially in elevation, of the general layout of a pneumatic con-

trol system constructed and arranged in accordance with the invention; Fig. 2 to Fig. 9, inclusive, are detail views serving to more completely illustrate various pieces of control apparatus that are shown in Fig. 1; Fig. 10 is a view, in side elevation, of a group of pipes or conduits corresponding to the familiar "train-line conductors" of the electrical or electro-pneumatic control systems; Fig. 11 is a diagrammatic view of the main circuits of an electric-motor system that is governed by my present auxiliary control system; Fig. 12 and Fig. 13 are developed views and Fig. 14, Fig. 15 and Fig. 16 are elevational views, of an auxiliary appliance that may be substituted for one of the pieces of control apparatus that is illustrated in Fig. 1; Fig. 17 is a semi-diagrammatic view of a modified form of the general apparatus layout, corresponding to Fig. 1; and Fig. 18 is a sectional view of a modification of one of the pieces of apparatus that are shown in Fig. 17.

Referring to Fig. 1 of the drawings, the pneumatic system shown comprises a fluid-pressure-operated controller-actuating mechanism 1; a primary governing means or manual control valve 2 corresponding to the familiar master controller of electrical systems; an automatic operating valve 3; an electro-pneumatic limit valve 4; an electro-pneumatic overload trip 5 that pneumatically communicates with the controller-actuating mechanism 1 for governing purposes to be set forth; and a fluid-pressure-operated controller-shifting apparatus 6.

The controller-actuating mechanism 1 comprises a pinion 9 which is rigidly secured to the circuit-governing member or operating shaft 10 of the main-circuit controller and which meshes with a reciprocating rack member 12, the opposite ends of which constitute pistons 13 and 14 that travel within suitable operating cylinders 15 and 16, respectively. A pipe or conduit 17 effects communication between the cylinder 15 and the electro-pneumatic overload trip 5, while a plurality of pipes or conduits 18, 19 and 20 pierce the walls of the cylinder 16 at predetermined points and respectively communicate with the automatic operating valve 3, the electro-pneumatic limit valve 4, and with a second and similar limit valve (not shown).

The mechanical operation of the controller-actuating mechanism 1 may be set forth as follows: Normally, as subsequently traced in detail, fluid pressure is admitted to the cylinder 16 but is excluded from the cylinder 15, which communicates with the atmosphere. Consequently, the apparatus is initially biased to the illustrated position. Upon the reversal of such initial conditions, that is, upon the release of fluid pressure from the cylinder 16 and the admission of fluid pressure to the cylinder 15, a downward movement of the pistons, as viewed in Fig. 1, is produced to effect a counter-clockwise rotative movement of the controller shaft 10, viewed from the right of the figure. To arrest such movement at any time it is merely necessary to re-admit fluid pressure to the cylinder 16, whereupon balanced high-fluid-pressure conditions obtain in the mechanism and a positive and reliable stoppage thereof is effected. To produce a backward movement of the mechanism, fluid-pressure conditions are caused to revert to the original unbalanced state, whereby the desired return movement toward the illustrated normal position is brought about.

Referring also to Fig. 2 and Fig. 3, the manual control valve 2 comprises a centrally-located shaft 25 upon which is loosely mounted a notching plate 26 that is provided with a set of peripheral teeth or projections 27 and a set of lateral teeth 28, each set respectively corresponding to operative positions *a* and *b* of the valve. A plurality of ports or apertures 29, 30 and 31 are provided, at selected points in the plate 26, for governing purposes to be described. Furthermore, a recess or depression 32 in the under-side of the plate 26 is provided for a similar purpose. A plurality of pipes or conduits 21, 33, 34 and 35, respectively effect communication between the manual control valve 2 and a second automatic operating valve (not shown) that is similar to the automatic valve 3, the electro-pneumatic overload trip 5, the reservoir or source of fluid pressure (not shown), and the automatic operating valve 3.

In the illustrated "off" position of the manual control valve 2, the pipe 33 registers with the port 29, while ports 30 and 31 are respectively located to register with pipes 35 and 21 in positions *a* and *b* of the control valve.

The valve structure further comprises a stationary base or mounting plate 40; an upper incasing member or shell 41; a handle member 42 and a helical spring 43 which operates between the shaft 25 and the notched plate 26 for the purpose of returning the control valve to the illustrated "off" position whenever pressure from the

train operator's hand is released from the handle member 42, thereby providing a "dead-man's release" feature, as hereinafter more fully set forth.

The handle member 42 is shown as comprising a body or bar 50, one end of which is detachably secured to the valve-shaft 25 and the other end of which is apertured to receive a pin 51 to which is attached the customary wooden grip 52. The lower end of the pin 51 rests upon the horizontal arm 75 of a bell-crank lever 53 which is pivoted upon a projection of the bar 50 at an intermediate point 54, the vertical arm of the bell-crank lever abutting against a link member 55 which is intermediately pivoted at 56 upon a projection 50^a of the bar 50. The link 55 has a pin-and-slot connection 57 with a lower slidable rod 58 and a pivotal connection 59 with an upper slidable rod 60, both rods extending through downwardly-extending supporting arms 50^b and 50^c of the bar 50.

A coil spring 61 tends to bias the rod 58 to engagement with the peripheral set of teeth 27 of the notching plate 26, while a stronger coil spring 62 normally biases both rods 58 and 60 to the illustrated positions. The inner end of the rod 60 abuts against the vertical arm 63 of a right-angled lever member which is intermediately pivoted at 64 upon the shell 41 of the valve and is provided with a dependent tongue 65 that is mounted upon a pivot 66 to operate within a groove of the shell, being biased downwardly to engage the lateral teeth 28 of the notched plate 26, by means of a flat spring 67 which is fastened to the shell 41.

Assuming that the manual control valve occupies the position illustrated in Fig. 2, a downward pressure from the train-operator's hand upon the grip 52 effects a corresponding or clockwise movement of the horizontal arm of the bell-crank lever 53, thereby causing a clockwise movement of the link 55 around its intermediate pivotal point 56 and thus producing a movement of the lower slidable rod 58 toward the left and of the upper slidable rod 60 toward the right. The lower rod 58 may thus engage the first peripheral tooth 27 (corresponding to position *a*) of the notching plate 26, and a subsequent rotative movement of the actuating handle in the counter-clockwise direction, as viewed in Fig. 1 or Fig. 3, produces a movement of the control valve 2 into its initial operative position *a*, where the valve may be maintained stationary as long as the downward pressure on the grip 52 obtains, by reason of the above-mentioned longitudinal movement of the upper rod 60, which permits the flat spring

67 to downwardly actuate the tongue 65 into locking engagement with the first lateral tooth 28 of the plate 26.

Thus, the lower slideable rod 58 and the 5 peripheral teeth 27 effect step-by-step movement of the manual control valve 2, the lateral teeth 28 and the interlocking mechanism that is associated with the upper slideable rod 60 serving to hold the valve 10 in each position and permit further "forward" operation of the valve while downward pressure from the operator's hand is maintained.

Whenever pressure upon the handle grip 15 52 is released by reason of incapacitation of the train operator, or otherwise, the predominating spring 62 returns the linkage mechanism to the position illustrated in Fig. 2, thereby allowing the helical spring 20 43 to immediately return the notched plate 26 and the handle member 42 to the normal or "off" position. It will be understood that other forms of "dead-man's release" mechanism may be employed in lieu of that 25 just described or, if desired, the manual control valve may be constructed in a simple manner which merely provides a step-by-step movement in either direction upon rotation of the actuating handle.

30 For the purpose of reversing the electrical relations of the armatures and field windings of the motors to be governed, the familiar fluid-pressure-operated device, embodying a pair of mechanically-connected 35 pistons that operate within a cylinder and are actuated in the one or the other direction, dependent upon the admission of fluid pressure to the corresponding end of the cylinder, is preferably provided. Since the 40 device just outlined is thoroughly familiar to those skilled in the art and, furthermore, generically resembles the controller actuating mechanism 1, no further illustration or 45 description thereof is believed to be necessary.

To control the above-mentioned admission of fluid pressure to the motor-reverser device, a manual auxiliary reversing apparatus 70 may be conveniently associated with 50 the manual control valve 2, as illustrated in Fig. 3. The auxiliary reverser 70 is shown as comprising a semi-cylindrical incasing member 71 that may be integrally, or otherwise, related to the shell 41 of the 55 valve 2, and an operating shaft having a rectangular head 72 that is inclosed on all sides but one by a collar 72^a, whereby operative access to the shaft head 72 may be obtained only when the manual reversing 60 valve occupies the illustrated intermediate or off position.

The rotatable shaft of the manual reverser is provided with an arcuate internal passage 73 which is adapted to effect communication between a reservoir-connected

70 pipe 74 and an outlet pipe 75 when the reverser is actuated by the familiar handle member 76 to the forward position that is indicated by dotted lines and the legend "Forward", whereby fluid pressure is admitted to the proper end of the main reverser to effect the desired motor-circuit connections. On the other hand, when the actuating handle 76 is moved from the intermediate or off position to the reverse 75 position, represented by dotted lines and the legend "Reverse", the passage 73 serves to join the supply pipe 74 with an outlet pipe 77, thus admitting fluid pressure to the opposite side of the main reverser. 80

By reason of the provision of the rectangular shaft head 72 and the inclosing collar 72^a, it will be appreciated that the actuating handle 76 can be operatively inserted or removed only when the apparatus 85 occupies the illustrated off position. The projecting arm of the actuating handle 76, in accordance with a customary practice, slides within a slot in the collar 72^a when the manual reverser is actuated to either of 90 its operative positions.

Furthermore, the location and shape of the shaft head 72 are made such that when the manual reverser 70 occupies its off position, the manual control valve 2 is prevented from movement to its operative positions, by reason of the mechanical interlocking of adjacent parts, but when the reverser 70 is actuated to either of its operative positions, sufficient clearance between 100 such adjacent parts is provided to permit the desired movement of the manual control valve 2. 95

The automatic operating valve 3 comprises a duplex structure having independent suitably chambered valve portions 7 and 8 that are located side-by-side, the portion 7 being provided with a double-ended plug valve member 22 which is normally biased, by a spring 23, to the illustrated position, 105 whereby communication between the manual control valve 2 and the electro-pneumatic limit valve 4 is cut off. An externally-protruding pin or stem 22^a has its upper end secured to the valve member 22 110 for a purpose to be set forth. The other chambered portion 8 is provided with a double-ended plug valve member 24 which is normally maintained in the illustrated position by reason of the mechanical connection 115 thereof with the other valve member 22, as about to be described in detail, and thus initially permits communication between the pipe or conduit 18 and a pipe 36 which leads directly to the reservoir. 120 When the valve occupies its lower position, communication is effected between the pipe 18 and the atmosphere by a suitable outlet port. The lower end of the valve member 24 is extended to form a pin 37, the exter- 125

130

- nal end of which is pivotally associated by a link 38, having an intermediate pivotal connection upon a lug 39 of the valve body, with the exterior portion of the pin 22.
5 Thus, a downward movement of the plug valve member 22 produces an upward movement of the plug valve member 24, and vice versa.

The electro-pneumatic limit valve 4, shown completely in Fig. 4, comprises a chambered cylinder or shell 80 having a single plug valve member 81 that normally permits communication between the pipe 19 and a pipe 82 which leads to the automatic operating valve 3 and which, in its upper position, shuts off communication between those pipes. A horizontally-extending oscillatable arm 83 has one end pivoted within the shell 80 at the point 84, and a right-angled link 85 is pivotally secured to the outer end of the arm 83 externally to the shell 80, the upper end of the link 85 being attached to a spindle 86 which is vertically movable within a bracket member 87 and is supported by the upper surface of the shell 80. A suitable magnetizable core 88 is mounted upon the spindle 86 and is adapted to be actuated to its upper position when an inclosing coil 89, which is connected in the main-motor circuit as diagrammatically illustrated in Fig. 11, is energized above a predetermined amount, whereby the link 85 and the arm 83 are likewise raised to effect actuation of the plug valve member 81 to its upper position. The valve thus performs a function similar to that of the well-known limit switch in electrical systems, as more fully described later.

Referring to Fig. 5, the electro-pneumatic over-load trip 5 comprises a duplex body member having independent suitably chambered portions 95 and 96 that are located side-by-side, the pipes 17 and 33 communicating with the portion 96 and the pipe 34 and a further pipe 97, which leads to the controller-shifting apparatus 6, communicating with the valve portion 95.

A double-ended plug valve 98 is biased by a helical spring 99 to the illustrated position within the valve portion 95, whereby access of fluid pressure from the supply pipe 34 to an aperture or passage 100 is cut off, while communication between the pipe 97 and an outlet port 101 through an internal passage 102 is permitted. A downwardly-extending pin 103 is integrally, or otherwise, secured to the plug valve member 98 to permit actuation thereof by an external agency, as subsequently set forth.

60 The valve portion 96 is similarly provided with a double-ended plug valve member 104 which is biased by a coil spring 105 to the illustrated position, thereby effecting communication between the pipes 33 and 17 through an internal passage 106 and nor-

mally cutting off communication between the pipe 17 and an outlet port 107 through an internal passage 108. The lower end of the plug valve member 104 is integrally, or otherwise, extended in the form of a pin or 70 rod 109, the lower end of which is in substantially horizontal alignment with that of the pin 103.

A slideable rod 110 has its upper end located in a centrally situated slot or recess 75 111 of the valve body and is provided, near its upper end, with a transverse bar or plate 112 for the purpose of striking the pins 103 and 109 when raised to its uppermost position. The bar or plate 112 preferably rests upon a coil spring 113 that surrounds the rod 110, thereby providing a cushioning effect when the bar strikes the pins.

The lower portion of the rod 110 has mounted upon it a suitable magnetizable core 114 which, in turn, is inclosed by an actuating coil 115 that is connected in circuit with the main motor or motors to be governed, as diagrammatically shown in Fig. 11. A magnetic keeper or armature 116 has one end pivoted at 117 and, upon a predetermined energization of the magnetizable core 114 by the coil 115, the armature 116 is raised to a substantially horizontal position, where it is held by means of a latch 118, of a familiar type, which is intermediately pivoted at 119 and is biased to a latching position by a suitable spring 120. Consequently, upon the occurrence of a predetermined overload current in the motor circuit, the core 114 is raised into such a position that the transverse bar 112 strikes the pins 103 and 109 and raises the plug valves 98 and 104 into their upper positions, where they are maintained by reason of the latching mechanism. To permit further operation of the system, the latch 118 may be manually, or otherwise, actuated to allow the armature 116 to drop to an inoperative position, whereby the overload trip is reset 100 in readiness for the next operation, in accordance with a familiar practice.

The controller-shifting apparatus 6 comprises a cylinder-and-piston device or other pneumatic engine 125; a double-diameter 115 cam member 126 and a resetting cam device 127, with both of which an oscillatable member or arm 128 is associated as hereinafter to be set forth; and a valve member 129 for governing the operation of the shifting apparatus under predetermined conditions.

The pneumatic engine 125 is shown in section in Fig. 1 and comprises a cylinder or incasing member 131 within which travels a piston 132 that is biased to one extreme position by means of a coil spring 133. The piston stem 134 constitutes an integral or otherwise operatively-related extension of the controller shaft 10, whereby a longitudinal movement of the piston 132 shifts the con- 125 130

troller shaft 10 a distance sufficient to quickly break contact between all of the active stationary and movable contact members of the controller, as subsequently explained. In this way, the motor circuits may be rapidly interrupted under predetermined conditions and, in particular, the controller may be returned to its initial position without requiring the opening of circuits in the reverse sequence to that employed during forward rotation. In this manner, undue wear and pitting and burning of contact members are obviated.

The cam member 126 comprises a portion 135 of relatively great diameter that corresponds to, and is employed during, the backward movement of the controller shaft. A second cam surface 136, of materially lesser diameter, corresponds to, and is utilized during, forward or operative movement of the controller shaft. A roller 137, or other suitable friction-reducing device, is employed for effecting engagement of the cam member 126 with the oscillatable arm 128.

The surface of the smaller-diameter cam portion 136 is substantially cylindrical, while the surface of the larger diameter portion 135 is cylindrical, for the most part, and is provided with a recess or depression 138 of a size corresponding to the roller 137, this recess normally housing the roller when the cam member 126 and the controller occupy the illustrated "off" position. The larger cam portion 135 is also provided with a tapered recess 139 of such a shape that the roller 137 will be quickly forced from the depression 138 to the small cam surface 136 upon a slight forward or clockwise movement of the controller, and the roller 137 rests upon the smaller cam surface 136 throughout subsequent forward operation. One or more lateral notches 135^a are provided to lift the roller 137 from the smaller-diameter to the larger-diameter cam surface upon backward controller movement.

The roller 137 is mounted upon a bolt or rod 140 which extends between spaced lugs 141 and 142 of the body portion 143 forming a part of the oscillatable arm 128. The end 50 of the body portion 143 that is remote from the roller 137 is pivotally mounted upon a stationary standard or bracket 145. A coil spring 146, surrounding the bolt 140, serves to bias the roller 137 toward the right, as viewed in Fig. 6, into the recess 138.

The resetting cam device 127 comprises a bar or rod 150 which is intermediately pivot-60 ed at 151 upon a projection 152 of the air-cylinder 131, for example, and in the upper position of the oscillatable arm 128, the rod 150 is adapted to engage a notch 153 of the lug 142 and thereby maintain the oscillatable arm 128 in its upper position to permit the admission of fluid pressure to the pneumatic engine 125 and thereby produce the pre-

viously-mentioned longitudinal shift of the controller shaft 10.

The lower end 154 of the rod 150 is adapted to engage a suitably configured cam surface or block 155 that is mounted upon the piston stem 134 just before the controller reaches its "off" position during returning movement, whereby the rod 150 is unlatched from the lug 142 to allow the oscillatable arm 128 to drop to its illustrated lower position.

The valve device 129 comprises a shell 160 with which communicates a supply pipe 161 and an outlet pipe 162 that leads into the pipe 97. A double-ended plug valve member 163 is normally biased by a coil spring 164 to the illustrated position, whereby the admission of fluid pressure to the outlet pipe 162 is prevented and the pipe 162 is placed in communication with the atmosphere through an outlet port 165 of the valve.

A pin or rod 166, constituting an extension of the plug valve member 163, projects through the shell 160 and is fastened to the upper end of a helical spring 167, the lower end of which is positioned over a suitable boss 168 upon the oscillatable arm 128. In this way, a resilient connection is provided between the arm 128 and the valve 129.

When the controller occupies its "off" position, the roller 137 rests within the recess 138 of the larger-diameter cam surface 135, as previously mentioned. Upon movement of the controller and of the cam member in the clockwise direction, as indicated by the arrow in Fig. 8, the roller 137 is forced by the inclined surface 139 to ride along the smaller cam surface 136 until the final forward position is reached.

Upon backward movement of the controller, the roller 137 is actuated upwardly by the wedging action of the corresponding notch 135^a and rides along the larger diameter cam surface 135. The arm 128 is latched in its upper position by reason of the engagement of the rod 150 of the resetting cam device 127 with the notch 153. Such upward movement further actuates the plug valve member 163 to permit the admission of fluid pressure to the pneumatic engine 125, thereby producing the desired longitudinal shift of the controller shaft 10, as previously described. The roller rides along the larger cam surface 135 until the recess 138 is reached, which occurs at approximately the same time that the resetting cam device 127 is disengaged from the oscillatable arm 128, whereby the roller 137 is allowed to drop into the recess 138 when the illustrated "off" position of the controller is attained.

The electrical circuits governed by, and the type of contact members embodied in, the main controller are immaterial to my present invention, but the familiar cam-operated type of control apparatus that is illustrated in Fig. 9 is preferably employed.

The apparatus in question comprises a pneumatic valve 170 which is actuated by the cams 11 that are mounted upon the controller shaft 10 to govern the admission of fluid pressure to a pneumatic engine 171 which, in turn, effects engagement of a set of stationary and movable contact members 172.

The valve 170 comprises a shell or incasing member 175, within which is located a double-ended plug valve member 176 that is biased to the illustrated position through the agency of a coil spring 177, whereby the admission of fluid pressure from a supply passage 178 to a distribution passage 179 is normally cut off, and an outlet port 180 is normally in communication with the distribution passage 179. The plug valve member 176 is provided with an upwardly-extending pin or rod 81 for the purpose of engaging the controller cam 11, whereby the operation of the contact members is effected. The pneumatic engine 171 comprises an operating cylinder 182, within which travels a piston 183 that is biased to its lower position by means of a helical spring 184.

Inasmuch as the illustrated coöperating stationary and movable contact members are of a well-known type, only a brief description thereof will be necessary. The movable contact member 185 is of the familiar copper-terminal type and is suitably mounted upon a movable arm 185^a which is intermediately pivoted at a point 186 and is supported through the agency of a bolt 187 located within an opening in the top supporting plate 188. The customary biasing spring 189, for maintaining the movable contact member 185 in the illustrated position, is provided. The stationary contact member 190 is of a similar type and is secured to the plate 188 in a similar and well-known manner.

Referring to Fig. 10, the set of horizontally-extending pipes 192 correspond to the familiar train-line conductors of electrical systems and are fitted with suitable couplings between adjacent vehicles, in order to permit multiple-unit operation thereof, as will be understood. The various pipes or conduits of Fig. 1 which it is necessary or desirable to interconnect in the several vehicles are represented by the sets of vertical pipes 193, which are numbered to correspond to Fig. 1.

In Fig. 11, a series-parallel control system of a familiar type, to which my present invention may readily be applied, is illustrated in a simplified manner. The system comprises supply-circuit conductors Trolley and Ground; a plurality of dynamo-electric machines respectively having commutator-type armatures A1 and A2 and field windings F1 and F2 of the series type; variable resistors R1, R2 and R3; the actuating coils 115 and 89 of the electro-pneumatic over-

load trip and the electro-pneumatic limit valve, respectively; and a plurality of switches of the type shown in Fig. 9, the coöperating stationary and movable contact members thereof being correspondingly designated in one instance. Since the illustrated system is of a familiar type, employing "bridging" transition from series to parallel relation, and also since the particular type of electrical system that is employed in conjunction with my present invention is immaterial thereto, no further illustration or description of the system is deemed to be necessary.

Assuming that the various parts of the control system occupy the respective positions that are illustrated in Fig. 1, the general operation of the system may be set forth as follows: Normally, fluid pressure is conveyed from the reservoir through pipe 36, the internal passage of the right-hand portion 8 of the automatic operating valve 3 and pipe 18 to the operating cylinder 16 of the controller-actuating mechanism 1. On the other hand, the outer end of the operating cylinder 15 communicates through pipe 17, internal passage 104 of the electro-pneumatic overload trip 5 and pipe 33 to the atmosphere through port 29. Consequently, the controller-actuating mechanism 1 is maintained in the illustrated position by reason of the unbalanced condition of fluid pressure therein whenever the manual control valve 2 occupies its "off" position.

Upon actuation of the manual control valve 2, by means of the previously described actuating handle, to position *a*, corresponding to series acceleration, the port 29 is removed from communication with the pipe 33 which is placed in communication with the supply pipe 34 through the recess 32 in the under-side of the notched plate 26. In this way, fluid pressure is directly admitted through the manual control valve 2 to the operating cylinder 15 of the controller-actuating mechanism 1, but no movement thereof occurs, since the fluid pressures are balanced in the two cylinders 15 and 16.

However, the port 30 in the notched plate 26 of the manual control valve 2 registers with the pipe 35 in position *a* of the valve, whereby the internal passage of the left-hand portion 7 of the automatic operating valve 3 is connected to the atmosphere and, consequently, the pneumatic pressure is conducted from the cylinder 16 through the pipe 19, the electro-pneumatic limit valve 4 and the pipe 82 underneath the upper plug of the valve member 22 of the automatic operating valve. The fluid pressure initially present in the operating cylinder 16 is thus allowed to gradually exhaust through the port 30 of the manual control valve 2. In this way, a gradual movement 115

of the pistons 13 and 14 downwardly, as viewed in Fig. 1, is produced by reason of the unbalancing of the fluid pressures in the two cylinders 15 and 16.

Such unseating or upward movement of the plug valve member 22 effects a simultaneous downward movement or seating of the plug valve member 24 in the valve portion 8, by reason of the mechanical interconnection between the valve members, as previously set forth. Thus, the supply of fluid pressure from the reservoir to the operating cylinder 16 through the pipe 18 is shut off to permit the desired movement of the controller-actuating mechanism 1.

Such movement will continue until the piston 14 prevents communication of the lower or active portion of the operating cylinder 16 with the side outlet pipe 19. Under such conditions, the fluid pressure maintaining the plug valve member 22 of the automatic operating valve 3 unseated, is removed to permit the spring 23 to actuate the plug valve members 22 and 24 to the illustrated position, whereupon fluid pressure is again conducted from the reservoir through the right-hand portion 8 of the valve 3 to the operating cylinder 16, and the resultant balancing of fluid pressures in the mechanism effects a positive and reliable stoppage thereof in a position corresponding to the full series operating position of the governed motors.

However, automatic regulation of the controller movement, in accordance with predetermined conditions, in this case the current traversing the motors and, therefore, traversing the actuating coil 89 of the electro-pneumatic limit switch 4, is provided. Whenever the plug valve member 81 of the limit valve is actuated to its upper or closed position in the manner hereinbefore described, communication between the pipes 19 and 82 is directly interrupted. In this way, fluid pressure is removed from the left-hand portion 7 of the automatic operating valve 3 to permit the previously-described actuation of the plug valve members 22 and 24 by the spring 23 to the illustrated position, thereby readmitting fluid pressure from the reservoir through the pipes 36 and 18 to the operating cylinder 16 and effecting a rapid stoppage of the pistons 13 and 14.

Upon the occurrence of overload conditions, whereby a predetermined current corresponding to the setting of the overload trip 5 traverses the actuating coil 115 thereof, fluid pressure is admitted from the supply pipe 34 through the internal passage 100 of the left-hand portion 95 of the overload trip as soon as the plug valve member 98 has been raised to its upper position, in accordance with the previously-described operation of the device, and thence fluid pressure is conveyed through the pipe 97 to the

cylinder 131 of the pneumatic engine 125. The piston 132 thereof is immediately moved toward the right against the action of the spring 133 to effect the previously-described longitudinal movement or shifting 70 of the controller shaft 10, whereby the various controller cams 11 are longitudinally disengaged from the actuating pins 181 of the valve members 170 that control the operation of the various sets of contact members that are illustrated in Fig. 9. Thus, all controller circuits are opened immediately upon the occurrence of an overload current. 75

The actuation of the right-hand plug valve member 104 of the overload trip 5 cuts 80 off communication between pipes 33 and 17 and connects the outlet port 107 with the pipe 17, whereby fluid pressure is exhausted from the operating cylinder 15, and since fluid pressure is present in the other operating cylinder 16, a return movement of the mechanism to the illustrated "off" position takes place. 85

As previously described, to permit the further operation of the system after the 90 occurrence of overload conditions, the manual control valve 2 is returned to its "off" position and the overload trip 5 is then reset, either manually or by remote control in any of the ways familiar in the art, by releasing the latching mechanism that is shown in Fig. 5. 95

The above-recited automatic operation of the controller-actuating mechanism 1, in accordance with the movements of the electro-pneumatic limit valve 4 will continue until the outlet pipe 19 from the operating cylinder 16 is covered by the piston 14, as already explained. 100

To effect further operation of the control system, such as the parallel-connected acceleration of the governed motors, the manual control valve 2 is actuated to its final operative position *b* in the manner previously described in connection with Fig. 2 110 and Fig. 3, whereby communication is maintained between the pipes 33 and 34 by the recess 32 in the notched plate 26, but the registration of the outlet port 31 with the pipe 21 is substituted for the previous registration of the outlet pipe 30 with the pipe 35. 115

In this way, the other set of governing devices, comprising the previously-mentioned second automatic operating valve (not shown) and second electro-pneumatic 120 limit valve (not shown) are rendered operative to control the action of the controller-actuating mechanism 1 in the previously described automatic manner until the opening of the side outlet pipe 20 from the operating cylinder 16 is governed by the piston 14. This condition corresponds to the end of the piston travel and to full parallel connection of the governed motors that are shown in Fig. 11. 125

The structure illustrated in Fig. 12 to Fig. 16, inclusive, constitutes a modification of the controller-shifting apparatus 6 that operates solely through the mechanical interlocking of parts, thereby obviating the necessity for a pneumatic engine and a controlling valve.

The structure shown comprises a three-part or triple-operating-surface cam member 200 having a substantially cylindrical end portion 201 of relatively small diameter that corresponds to forward movement of the controller; an end portion 202 of irregular shape and an intermediate portion 203 of relatively great diameter, which is provided with a plurality of alternately occurring, diagonally-extending ridges or projections 209 and grooves or depressions 210. The cam member 200 is rigidly secured to a shaft or axle 204 which constitutes an extension of the controller shaft 10, corresponding to the structure that is shown in Fig. 1.

The apparatus further comprises an engaging or roller-carrying member 205, which is best shown in Fig. 16, and a main shifting spring arrangement 206.

The roller-carrying member 205 comprises a contact roller 214 which is rotatively moved transversely to the direction of rotation of the controller shaft and which is mounted upon a spindle that extends through arms 216 and 217 of the body member 218, the roller 214 being biased to its illustrated lower position by a spring 219 that is located between the arms 216 and 217. A second coil spring 220 operates between the body member 218 and a stationary portion 221 of the controller frame, the outer end of the body member 218 being provided with a retaining nut 222, whereby the body member 218 is adapted to slide within the stationary frame member 221 in opposition to the action of the spring 220.

The main shifting spring arrangement 206 comprises a pin or shaft 225 which constitutes a further extension of the controller shaft 10 and is designed to slide through an aperture in a second stationary bracket or frame portion 226. A powerful spring 227 is located between the bracket 226 and a collar 228 of the shaft 225 the spring being adapted to normally maintain the controller shaft in the operative or contact-permitting longitudinal position.

Assuming that the various parts of the structure occupy the illustrated positions corresponding to the "off" position of the controller the operation of the controller-shifting apparatus may be set forth as follows: Upon forward movement of the controller through the agency of the actuating mechanism 1 in the direction indicated by the various arrows, the roller 214 is forced

out of the initial groove 210 corresponding to the "off" position, as most clearly shown in the developed view, Fig. 12, into sliding end-surface engagement with the small-diameter cylindrical portion 201 of the cam member 200. No longitudinal movement of the cam member or controller shaft is effected thereby, since the spring 220 is of materially smaller strength than the main spring 227. The roller 214 slides along the cam surface 201 until the next groove or depression 210, corresponding to the first operative position α' of the controller, is reached, whereupon the roller is retracted by the spring 220 into the groove, as indicated by the dotted circle in Fig. 12. Further forward movement of the controller from notch to notch effects a repetition of the action just recited.

However, upon backward movement of the controller from any position, the roller 214 rides along the wedge-shaped surface of the corresponding ridge or projection 209 and is thus forced to a position of engagement with the other end cam portion 202 which, for the most part, has a diameter smaller than that of the bottom surface of the grooves 210, and contact of the roller with the cam portion 202 is thus effected by the downward biasing action of the vertical spring 219. The collar or shoulder 228 upon the shaft extension 225 is positioned to be engaged by the nut 222 after a slight retractive movement thereof toward the left has occurred. Consequently, the further action of the cam ridges 209, instead of compressing the spring 220, causes a longitudinal shift of the cam member 200 and, therefore, of the controller shaft 10, toward the right, since the spring 227 is sufficiently powerful to prevent compression thereof by the wedging action just described. In this way, the desired longitudinal movement of the controller shaft to open up the various sets of contact members occurs rapidly and inherently upon a slight backward movement of the controller without requiring the use of a pneumatic engine or other power-actuated device.

The controller shaft is maintained in the shifting position during the further backward movement of the controller by reason of the smaller diameter of the cam surface 202 until a region marked α , which corresponds to the "off" position of the controller, is reached. At the central point of the region α , the cam surface 202 and the bottom surface of the corresponding groove 210 are substantially tangent, so that the expansive action of the spring 220 forces the roller 214 into the illustrated normal or initial position, while the release of the roller 214 from engagement with the left-hand face of the intermediate cam portion 203 permits

the main spring 227 to retract the controller shaft to its initial or contact-permitting position.

Reference may now be had to Fig. 17, 5 which semi-diagrammatically illustrates a modified and somewhat simplified complete system corresponding to Fig. 1.

The system shown comprises a fluid-pressure-operated controller-actuating mechanism 231; a manually-actuated pneumatic control valve 232; an automatic operating valve 233; an electro-pneumatic limit valve 234; an electro-pneumatic overload trip valve 235; a fluid-pressure-operated main 10 reverser 236; a manually-operated master reverser valve 237; and a plurality of train pipes 238.

It will be noted that, in the present system, only a single automatic operating valve 20 and a single limit valve are necessary in lieu of the two valves of each kind that are required in the system shown in Fig. 1 and, further, that the number of train pipes has been decreased.

25 The controller-actuating mechanism 231 is similar to the previously-described actuating mechanism 1, comprising a rack member 240 which meshes with the pinion 9 on the controller shaft 10 and the opposite 30 ends of which rack member constitute pistons 241 and 242 that travel within suitable operating cylinders 243 and 244, respectively. A combined inlet and outlet pipe 245 serves to connect the outer end of the 35 cylinder 231 to the electro-pneumatic overload trip valve 235, while the outer end of the other operating cylinder 244 is provided with two pipes or conduits 246 and 247 which respectively communicate with 40 opposite ends of the automatic operating valve 233.

The manual control valve 232 is shown as comprising a movable plate or disk 248 which is rigidly mounted upon a centrally-located shaft 249 and which is provided with a plurality of outlet ports 250 and 251 that are operative when the valve occupies the illustrated normal or "off" position, as subsequently more fully set forth. The plate 50 248 is further provided with a plurality of recesses or depressions 252 and 253, in its under surface, for the purpose of effecting communication between pairs of pipes or conduits 254 and 255, and 256 and 257, respectively. The pipe 254 leads into the master reverser valve 237; the pipe 255 is a supply pipe communicating directly with the reservoir or other source of fluid pressure; the pipe 256 is connected to the limit valve 234; and the pipe 257 communicates with the overload trip valve 235 and with the pneumatic reverser 236, as hereinafter traced in detail.

In the present instance, the manual control valve 232 may be provided with an

actuating device similar to that used in the familiar engineer's valve for air-braking systems or, if desired, the actuating mechanism shown in Fig. 2 and Fig. 3 may be associated with the movable plate 248.

70

The automatic operating valve 233 comprises a duplex tubular incasing member 260, within which is centrally positioned two aligned valve pins or stems 261 and 261^a that are respectively provided with an upper 75 plug valve 263 and a lower plug valve 264. An intermediately located piston 262 is rigidly mounted upon the stem 261^a, and a spring 266 serves to resiliently connect the two valve rods. A plurality of further coil 80 springs 265 and 267 are provided to respectively bear downwardly against the upper plug valve 263 and the lower plug valve 264, whereby the various movable elements are normally biased to the illustrated positions.

85 Outlet ports 268 and 269 are provided for the upper and the lower portions, respectively, of the automatic operating valve, while pipes or conduits 246 and 270, communicating respectively with the operating cylinder 244 and the reservoir, are connected to the upper valve portion; and pipes 247 and 271, communicating, respectively, with the operating cylinder 244 and the limit 95 valve 234, lead into the lower valve portion.

90 The electro-pneumatic limit valve 234 is of the same type as the previously-described valve 4, comprising, in general, an incasing shell 280 and a plug valve 281, the stem 282 of which is associated with an actuating coil that is energized by the motor current 100 similarly to the apparatus shown in Fig. 1. A lower outlet port 283 for the valve is provided, and an inlet pipe 284 communicates 105 through train pipe 285 to the pipe 256.

95 The electro-pneumatic overload trip valve 235 is simplified in form from the valve 5 of Fig. 1 and comprises essentially an incasing member 288 and a plug valve 289, 110 the stem 290 of which is adapted to be upwardly actuated when the current traversing an energizing coil (not shown) that is connected in the motor circuit, is excited above a predetermined degree. The valve 115 235 is provided with a lower outlet port 291 and an upper inlet pipe 292 which communicates with the pipe 257.

120 The main reverser 236 is of a type that is familiar in general, comprising a plurality of pistons 295 and 296 which respectively travel within suitable operating cylinders 297 and 298 and are rigidly connected by a stem or rod 299 having an intermediate pivotal joint 300 with an oscillatable link 125 or arm 301 which is rigidly secured to the movable member of a two-way valve 302 having an internal passage 303 that communicates, in the position shown, with pipes 304 and 305, respectively leading to the 130

cylinder 297 and to the pipe 257. A further pipe 306 which is closed in the illustrated position of the two-way valve communicates through pipe 310 to train pipe 311 and also 5 to a pipe 312 which is connected to the master reverser valve 237. A further pipe 307 effects communication from the cylinder 297 through train pipe 308 to pipe 309 which leads into the master reverser valve 237.

10 The manually-operated reverser valve 237 comprises a centrally-located operating shaft 314, upon which is rigidly mounted a plate or disk 315 having an internal passage 316 which, in the illustrated position, 15 effects communication between pipes 254 and 309. A suitable actuating handle for the valve is indicated at 317. The illustrated valve position corresponds to "forward" movement of the main controller, 20 while a clockwise movement of the handle 317 from the illustrated "forward" position to the dotted-line position marked "Reverse" serves to effect communication between the pipes 254 and 312 by the internal 25 passage 316.

The manual control valve 232 and master reverser valve 237 are preferably interlocked mechanically, as illustrated in Fig. 3, for example, to prevent undesirable relative movement of the two valves, corresponding to the customary interlocking between electrical master controllers and master reversers.

Assuming that the main reverser 236 occupies the illustrated forward position and that the master reverser valve 237 is actuated to its "reverse" position, upon actuation of the manual control valve 232 to its first operative position, fluid pressure is 30 conveyed from the reservoir through pipe 255, recess 252 in the under side of the plate 248 of the manual control valve, pipe 254, which registers with the outlet port 250 only in the "off" position of the control 35 valve, thence through internal passage 316 of the master reverser valve 237, and pipes 312 and 310 to the operating cylinder 298. In this way, fluid pressure is admitted to 40 the reverse cylinder of the main reverser, and the two-way valve 302 is actuated into such a position that pipes 305 and 306 are placed in communication through the internal 45 passage 303 of the valve, whereby operation of the controller-actuating mechanism 231 is permitted, as subsequently described. A corresponding operation takes place whenever the main reverser 236 occupies its reversed position, and the master reverser valve 237 is moved to its forward 50 position, while the manual control valve 232 occupies its first operative position.

When the various pieces of control apparatus occupy the illustrated positions, the operating cylinder 243 of the controller-actuating mechanism 231 is connected

through pipe 245, internal passage of the electro-pneumatic overload trip valve 235, pipes 292 and 305, internal passage 303 of the two-way valve 302, pipes 304 and 307, train pipe 308, pipe 309, internal passage 70 316 of the master reverser valve 237 and pipe 254 to outlet port 250, whereby the operating cylinder 243 is normally placed in communication with the atmosphere. On the other hand, the operating cylinder 244 75 communicates through pipe 246, internal passage of the automatic operating valve 233 above the plug 263 and pipe 270 to the reservoir, whereby fluid pressure is normally admitted to the cylinder 244 to bias the 80 controller-actuating mechanism to the illustrated position.

Assuming that the various parts of the control apparatus occupy the illustrated positions, the complete operation of the system may be set forth as follows: Upon actuation of the manual control valve 232 to its first operative position, fluid pressure is conducted from the reservoir through pipe 255, recess 252 and pipe 254, internal passage 316 of the master reverser valve, pipe 309, train pipe 308, pipes 307 and 304 (no movement of the main reverser occurring, since it already occupies its forward position), and thence through internal passage 90 303 of the two-way valve 302, pipes 305 and 292, an internal passage of the electro-pneumatic overload trip valve 235, in its illustrated lower position, and pipe 245 to the operating cylinder 243 of the controller-actuating mechanism 231.

However, no movement thereof occurs at this time by reason of the balanced fluid-pressure conditions in the two cylinders 233 and 234. Fluid pressure is also conveyed 105 through a branch pipe 257 from the pipe 305 to the recess 253 in the under side of the plate 248 of the manual control valve, pipe 256, train pipe 285, pipe 284, internal passage of the electro-pneumatic limit valve 110 234 in its illustrated lower position and pipe 271 to the automatic operating valve 233.

The influx of fluid pressure to the valve effects an elevation of the piston 262 to correspondingly raise the plug valves 263 and 264 to their upper positions. In this way, fluid pressure is exhausted from the operating cylinder 244 through pipe 247 and internal passage of the automatic operating valve below the plug valve 264 and thence 120 to the atmosphere through outlet port 269. Such gradual release of fluid pressure from the cylinder 244 permits a movement of the pistons 241 and 242 toward the right, since high fluid pressure is present in the other 125 operating cylinder 243. Such piston movement effects the desired rotative actuation of the controller shaft 10 in the previously-described manner.

The movement of the controller shaft is 130

interrupted whenever the electro-pneumatic limit valve 234 is raised to its upper position, whereby fluid pressure is shut off from the inlet pipe 271 to the automatic operating valve 233, thus permitting the spring 267 to return the plug valves 263 and 264 to the illustrated lower positions. In this way, fluid pressure is re-admitted from the reservoir through the automatic operating valve 10 233 to the operating cylinder 244 whereby a positive and reliable stoppage of the controller-actuating mechanism is effected. Automatic step-by-step operation of the controller shaft is thus produced, in accordance with the movements of the electro-pneumatic limit valve 234.

Upon the occurrence of an overload current which effects the actuation of the electro-pneumatic overload trip valve 235 to its upper position, the fluid pressure in the operating cylinder 243 is immediately exhausted through the pipe 245 and internal passage of the trip valve beneath the plug 289 and thence through the outlet port 291. Thus, movement of the controller-actuating mechanism toward the illustrated "off" position is produced as long as the overload conditions are maintained, since the electro-pneumatic limit valve 234 also occupies its upper position at this time, thereby permitting the admission of fluid pressure to the operating cylinder 244.

To prevent the controller-actuating mechanism 231 from stopping in a position intermediate the desired controller notches, an auxiliary cam mechanism may be employed to interconnect the automatic operating valve 233 with the controller shaft 10. Such a mechanism may comprise a cam plate or disk 275 which is provided with a plurality of lateral recesses or depressions 276, for the purpose of receiving the lower end of the valve spindle 261 in the respective "notches" or positions of the controller shaft 45 10 that correspond to the desired electrical connections. The cam plate 275 is mounted upon a stem or rod 277 which constitutes an extension of the controller shaft 10. Consequently, when the electro-pneumatic limit 50 valve 234 is actuated to cut off fluid pressure from the lower portion of the automatic operating valve 233 and thereby tend to permit the movement thereof to the illustrated position, such movement is, in reality, 55 prevented by the cam plate 275 until the next recess 276 is reached. In this way, the travel of the controller from one notch to the next notch is insured and false connections or burning of electrical contact 60 members is precluded.

The simplified form of automatic operating valve that is shown in Fig. 18 may be employed in lieu of the illustrated valve 233, whereby the pipe 247 is dispensed with. The 65 valve in question comprises a shell or in-

casing member 325 with the upper and lower ends of which the pipes 270 and 271 respectively communicate. A movable spindle 326 is provided at opposite ends with a plug valve 327 and a piston 328. A coil spring 329, acting between a lower fixed valve-seat 330 and the piston 328, serves to bias the movable valve parts to the illustrated position, whereby communication is normally established from the supply pipe 270 through an internal passage 331 to the pipe 246, which leads into the operating cylinder 244 of the controller-actuating mechanism 231. An intermediately located outlet port 332 is normally shut off by the plug valve 327 from communication with the pipe 246. 70 75 80

In view of the similarity of the automatic operating valve just described to the valve 233, only a brief description of its operation will be necessary. When fluid pressure is admitted through the pipe 271 from the manual control valve 232 and the electro-pneumatic limit valve 234, the piston 328 is forced upwardly to seat the plug valve 327 in its upper position, whereby communication between pipes 270 and 246 is interrupted to effect movement of the controller-actuating mechanism 231 in a manner previously described, by permitting the release of fluid pressure from the operating cylinder 244, through the pipe 246 and beneath the plug valve 327 to the outlet 332. Upon the lifting of the electro-pneumatic limit valve 234, the supply of fluid pressure to the pipe 271 is cut off, thereby permitting the coil spring 329 to return the automatic operating valve to the illustrated normal position and arrest the movement of the controller-actuating mechanism.

Some form of controller-shifting apparatus, such as that illustrated in Fig. 6 to Fig. 8, inclusive, or Fig. 12 to Fig. 16, inclusive, is preferably associated with the controller shaft 10 of Fig. 17, for the previously-described purpose of opening all contact members upon a backward movement of the controller to prevent burning and undue wear of the contact members. 105 110

As an operating economy, the pipes or conduits leading directly from the reservoir to the manual control valve may be of relatively large diameter, while the distributing pipes that communicate with the various pieces of control apparatus may be of smaller diameter. In this way, a relatively small volume of operating fluid is required, and the increased pressure thereof in the smaller pipes results in a quick and positive action of the automatic operating valve.

It will be appreciated that my all-pneumatic control systems may readily be adapted for use with either automatic or non-automatic acceleration of the governed motors. Furthermore, the electrical circuits will not be initially closed unless the fluid- 130

pressure is sufficient to adequately control the vehicle, thus providing a desirable safety feature.

I do not wish to be restricted to the specific structural details or arrangement of parts herein set forth, as various other modifications thereof may be effected without departing from the spirit and scope of my invention. I desire, therefore, that only such limitations shall be imposed as are indicated in the appended claims.

I claim as my invention:

1. A control system comprising a multi-position circuit-governing member, fluid-pressure operated means for actuating said member in the one or the other direction, valve means normally biased to a closed position but operative during actuation of said member to permit the release of fluid pressure from one side of said actuating means, and means dependent upon predetermined conditions for automatically restoring the normal biasing effect in said valve means.

2. A control system for dynamo-electric machines comprising a rotatable machine-circuit-governing member, a cylinder-and-piston apparatus for actuating said member in the one or the other direction, duplex valve means normally biased to a closed position but having an open passage during actuation of said member to permit the release of fluid pressure from one side of said actuating means, and further valve means dependent upon predetermined machine-current conditions for automatically restoring the normal biasing effect in said duplex valve means.

3. A control system for dynamo-electric machines comprising a rotatable machine-circuit-governing member, a cylinder-and-piston apparatus for actuating said member in the one or the other direction, duplex valve means normally biased to a closed position but having an open passage during actuation of said member to permit the release of fluid pressure from one side of said actuating means, manual control means for normally admitting fluid pressure to that side, means for actuating said control means to admit fluid pressure to the other side of said actuating means to effect movement thereof, and further valve means dependent upon predetermined machine-current conditions for automatically restoring the normal biasing effect in said duplex valve means to arrest said movement.

4. A control system comprising a multi-position circuit-governing member, fluid-pressure-operated means for actuating said member in the one or the other direction, valve means normally biased to a closed position but operative during actuation of said member to permit the release of fluid

pressure from one side of said actuating means, means dependent upon predetermined conditions for automatically restoring the normal biasing effect in said valve means, and pneumatic means dependent upon other conditions for automatically effecting the return movement of said circuit-governing member.

5. A control system for dynamo-electric machines comprising a rotatable machine-circuit-governing member, a cylinder-and-piston apparatus for actuating said member in the one or the other direction, duplex valve means normally biased to a closed position but having an open passage during actuation of said member to permit the release of fluid pressure from one side of said actuating means, further valve means dependent upon predetermined machine-current conditions for automatically restoring the normal biasing effect in said duplex valve means, and pneumatic means dependent upon higher-current conditions for automatically effecting a reversal of fluid-pressure conditions in said apparatus and a return movement thereof.

6. A control system for dynamo-electric machines comprising a rotatable machine-circuit-governing member, a cylinder-and-piston apparatus for actuating said member in the one or the other direction, duplex valve means normally biased to a closed position but having an open passage during actuation of said member to permit the release of fluid pressure from one side of said actuating means, further valve means dependent upon predetermined machine-current conditions for automatically restoring the normal biasing effect in said duplex valve means, means for longitudinally shifting said circuit-governing member to interrupt the machine circuits, and pneumatic means dependent upon relatively high-current conditions for automatically effecting the operation of said longitudinal shifting means.

7. A control system for dynamo-electric machines comprising a rotatable machine-circuit-governing member, a cylinder-and-piston apparatus for actuating said member in the one or the other direction, duplex valve means normally biased to a closed position but having an open passage during actuation of said member to permit the release of fluid pressure from one side of said actuating means, further valve means dependent upon predetermined machine-current conditions for automatically restoring the normal biasing effect in said duplex valve means, means for longitudinally shifting said circuit governing member to interrupt the machine circuits, and pneumatic means dependent upon relatively high-current conditions for automatically effecting

the operation of said longitudinal shifting means and for effecting a return movement of the circuit-governing member.

8. A control system for dynamo-electric machines comprising a rotatable machine-circuit-governing member, a cylinder-and-piston apparatus for actuating said member in the one or the other direction, a manual control valve for primarily and pneumatically governing said apparatus, a duplex automatic operating valve normally biased to a position permitting the admission of fluid pressure to one side of said apparatus but having an open passage during actuation of the apparatus to permit the release of fluid pressure from said one side and through said manual control valve, an electro-pneumatic limit valve interposed between said automatic operating valve and said one side of said apparatus for interrupting the supply of fluid-pressure thereto and allowing the operating valve to assume its normal biased position under predetermined machine-current conditions, a device for pneumatically shifting said circuit-governing member longitudinally, and an electro-pneumatic overload trip valve for admitting fluid pressure to said shifting device and for pneumatically effecting the return movement of said cylinder-and-piston apparatus under predetermined relatively high machine-current conditions.

9. A control system for dynamo-electric machines comprising a rotatable machine-circuit-governing member, a cylinder-and-piston apparatus for actuating said member in the one or the other direction, a pneumatically-operated main reverser, a manual control valve and a manual reverser valve for pneumatically and conjointly governing said apparatus and said reverser in a primary sense to produce a movement of the apparatus in the one or the other direction when the reverser occupies an operative position, a duplex automatic operating valve normally biased to a position permitting the admission of fluid pressure to one side of said apparatus but having an open passage during actuation of the apparatus to permit the release of fluid pressure from said one side, an electro-pneumatic limit valve interposed between said automatic operating valve and said manual control valve for interrupting the fluid-pressure supply and allowing said operating valve to assume its normal biased position under predetermined machine-current conditions, and an electro-pneumatic over-load trip valve for effecting the release of fluid pressure from the other side of said cylinder-and-piston apparatus under predetermined relatively high machine-current conditions.

10. In a pneumatic controlling apparatus, the combination with coöperating stationary and movable valve parts, of means for bias-

ing said movable valve part to a predetermined position, and actuating means normally biased to a disengaged position and dependent upon the application of manual pressure and subsequent rotative movement for actuating said movable valve part in a step-by-step manner and for locking it upon the completion of each step against return movement by said valve-biasing means.

11. In a pneumatic controlling apparatus, the combination with a stationary valve part and a coöperating rotatable valve part having a plurality of peripheral and also lateral teeth, of a spring for biasing the rotatable valve part to its "off" position, and actuating means comprising a plurality of slidable members, respectively corresponding to said peripheral and said lateral teeth, normally biased to a disengaged position, a grip member dependent upon manual downward pressure and subsequent rotative movement for effecting engagement of one of said slidable members with said peripheral teeth and produce step-by-step movement and for actuating the other slidable member to effect locking with said lateral teeth upon the completion of each step to prevent return movement by said spring unless said manual pressure is removed.

12. A fluid-pressure controlling device comprising a duplex chambered shell, a movable plug valve member associated with each chambered portion to complete various predetermined external communications, an intermediately pivoted link for externally connecting said plug valve members, and a single spring for normally biasing both said members to predetermined positions.

13. A fluid-pressure-controlling device comprising a chambered shell, a distributing pipe associated therewith, a plug valve member biased to open an upper and to close a lower communicating passage for said pipe, an oscillating arm mounted below said valve member and extending through one wall of said shell, a movable core and an actuating coil therefor positioned above said shell, and means for connecting said core to the outer end of said oscillating arm to effect movement of said valve to its upper position upon predetermined energization of said coil.

14. A fluid-pressure controlling device comprising a duplex chambered shell, a movable plug valve member associated with each chambered portion to complete various predetermined external communications, each valve member having an externally located portion, separate springs for biasing said valve members to certain positions, an actuating coil, and a core member therefor movable between said valve members to strike the external portions thereof upon predetermined energization of said coil and actuate the valve members to different positions against the action of said springs.

15. The combination with a rotatable member, of a fluid-pressure-operated device for normally biasing said member to a predetermined longitudinal position, a normally closed valve means for governing the admission of fluid pressure to said device, and cam means operative upon a predetermined rotative movement of said member to effect the opening movement of said valve means, whereby said member is longitudinally shifted to a second predetermined position.
16. The combination with a rotatable member, of a fluid-pressure-operated device for normally biasing said member to a predetermined longitudinal position, a normally closed valve means for governing the admission of fluid pressure to said device, an oscillatable arm for actuating said valve means, and a double-diameter cam member secured to said rotatable member, the smaller diameter surface engaging said arm during forward rotative movement to maintain the closure of said valve means, and the larger-diameter surface engaging said arm during backward movement of said rotatable member to effect the opening movement of said valve means, whereby the rotatable member is longitudinally shifted to a second predetermined position.
17. The combination with a rotatable shaft, of a cylinder-and-piston apparatus having its piston longitudinally secured to said shaft, a spring for normally maintaining the piston and shaft in a predetermined longitudinal position, a normally closed valve for governing the admission of fluid pressure to said apparatus, an oscillatable arm for actuating said valve, a double-diameter cam member secured to said shaft, the smaller-diameter surface engaging said arm during forward rotative movement to maintain the closure of said valve, and the larger-diameter surface engaging said arm during backward movement of said shaft to effect the opening movement of said valve, whereby the shaft is longitudinally shifted to a second predetermined position, and further cam means for effecting reengagement of said arm with said smaller-diameter surface when the shaft returns to its initial rotative position to effect a restoration thereof to its normal longitudinal position.
18. The combination with a rotatable shaft, of main means for normally biasing said shaft to a predetermined longitudinal position, a plural-operating-surface cam member secured to said shaft, an engaging member, and auxiliary means for normally

biasing said engaging member to engage an intermediate operating surface, said member being adapted to engage one adjacent operating surface in opposition to said auxiliary biasing means upon rotative movement of said shaft in the one direction and to engage another adjacent operating surface in opposition to said main biasing means upon rotative movement of said shaft in the other direction.

19. The combination with a rotatable shaft, of a main spring for normally biasing said shaft to a predetermined longitudinal position, a triple-operating-surface cam member secured to said shaft, a movable arm, and an auxiliary spring for normally biasing said arm to engage the intermediate operating cam surface, said arm being adapted to engage one outer cam surface in opposition to said auxiliary spring upon forward rotative movement of said shaft and to engage the other operating surface in opposition to said main spring upon backward rotative movement of said shaft to thus impart a longitudinal movement thereto.

20. The combination with a rotatable shaft, of a main spring for normally biasing said shaft to a predetermined longitudinal position, a cam member secured to said shaft and having an intermediately-located, diagonally-grooved surface, one outer surface of substantially cylindrical form and a second outer surface of smaller diameter than that corresponding to the grooves in said intermediate cam surface except in the region corresponding to the initial position of said shaft, a movable arm, and an auxiliary spring for normally biasing said arm to a position within one of said grooves, said arm being adapted to engage the cylindrical outer cam surface in opposition to said auxiliary spring during forward rotative movement of the cam member between grooves, and to engage the other and smaller-diameter cam surface in opposition to said main spring during backward rotative movement of the shaft to impart a longitudinal movement thereto by traveling along the smaller-diameter surface until said region is reached, whereupon said main spring restores the shaft to its normal longitudinal position and said auxiliary spring returns said arm to the corresponding groove.

In testimony whereof, I have hereunto subscribed my name this 30th day of June 1917.

WALTER H. SMITH.
